UNITED STATES PATENT OFFICE

ARTHUR T. KATHNER, OF NEW CUMBERLAND, WEST VIRGINIA

FURNACE CONVEYER

Application filed March 2, 1928. Serial No. 258,461.

This invention relates broadly to conveyers for metal annealing and heat treating furnaces, and more specifically to carrier devices for shaft conveyers.

5 The primary object of the invention is to provide, in association with a conveyer shaft, an improved form of conveyer disk and disk-interlocking means.

10 A further object is to provide a conveyer composed of a plurality of disks having hubs which are designed to interengage in such manner that leak-proof joints are formed therebetween.

15 In describing the invention in detail, reference is herein had to the accompanying drawings, in which—

Figure 1 is a view partly in section, illustrating a conveyer embodying my invention;

20 Figure 2 is an enlarged side elevation of the conveyer disk with its hub;

Figure 3 is a section on line 3—3, Fig. 2;

Figure 4 is an end elevation of a spacer; and—

25 Figure 5 is a section on line 5—5, Fig. 4.

Referring to said drawings, 1 designates a conveyer shaft, preferably of tubular form, having a uniform diameter throughout its length and which is designed to have its 30 opposite ends directed outwardly through the side walls of the furnace (not shown).

Keyed upon said shaft adjacent to its opposite ends at points located interiorly with respect to the furnace walls are collars 2 35 which have mounted therebetween a plurality of conveyer disks 3. Each of said disks has an integral sleeve-like hub 4 which has an internal diameter which materially exceeds the diameter of the shaft 1, and a

40 plurality of integral radially directed arms 5 carried by said hub adjacent to each of its ends seat upon the shaft and maintain said hub in concentric relation to said shaft.

Each hub has its opposite ends of male 45 and female forms, the male end being exteriorly tapered and being adapted to fit snugly within the interiorly tapered female end 7 of the next adjacent hub, or with the corresponding female end of a spacer 50 8 which substantially corresponds in form

with the hubs 4 except that the encircling disk 3 is omitted therefrom. Said spacers, which may have any desired length, are designed for employment to space the disk hubs away from the end portions of the 55 shaft and, when desired, to space the disks apart a suitably greater distance than when such hubs are arranged in interengaged relation.

Each of the male ends 6 of the hubs carries exteriorly thereof one or more relatively spaced lugs 9 adapted to be received within correspondingly shaped and spaced recesses 10 provided therefor interiorly of the female ends of adjacent hubs. As herein shown at 11, the lugs 9 formed on the male ends 6 have their outer faces inclined substantially to correspond with the exterior taper or inclination of said ends.

As indicated, each spacer 8 embodies integral radial arms 5^a, a male end 6^a and a female end 7^a and the female end being provided with recesses 10^a.

Following mounting of the disk hubs 6 and the spacers 8 on the shaft 1, the interiors thereof, or the spaces between such hubs or spacers and the shaft are packed with asbestos fiber or other suitable heat resisting material or composition 12 which serves to insulate the shaft 1 from the high temperatures carried within the furnace.

It will be noted that the joints between the hubs and spacers constructed as hereinbefore described are, in effect, of ship-lap type throughout and that, consequently, loss 85 of the heat resisting material or composition through leakage or sifting at such joints is effectually prevented.

What is claimed is—

1. In a conveyer for furnaces, a shaft, a plurality of conveyer disks carried by said shaft, each disk having a sleeve-like hub with its internal diameter materially exceeding the diameter of said shaft, said hubs having male and female ends for interfitting 90 with the adjacent non-corresponding ends of adjacent hubs, each of said female ends being provided with spaced internal recesses and each of said male ends having corresponding exterior lugs fitted within the re- 100

cesses of the next adjacent hub, each hub having a plurality of relatively spaced radial arms seated in embracing relation to said shaft.

5. 2. In a conveyer for furnaces, a shaft, a plurality of conveyer disks carried by said shaft, each disk having a sleeve-like hub with its internal diameter materially exceeding the diameter of said shaft, each of said 10 hubs having a plurality of radial arms seated upon said shaft whereby it is maintained in concentric relation to the latter, each hub having male and female ends whereby are formed joints of ship-lap type with the ends 15 of adjacent hubs, the female ends being provided interiorly thereof with relatively spaced recesses and the male ends carrying exteriorly thereof integral similarly spaced lugs fitted within the recesses of the next 20 adjacent hub, and a packing of heat insulating material between said hubs and the shaft.

3. In a conveyer for furnaces, a shaft, a plurality of conveyer disks carried by said 25 shaft, each disk having a sleeve-like hub with its internal diameter materially exceeding the diameter of said shaft, each of said hubs having a plurality of radial arms seated upon said shaft whereby it is maintained 30 in concentric relation to the latter, each hub having male and female ends whereby are formed joints of ship-lap type with the ends of adjacent hubs, the female ends being provided interiorly thereof with 35 relatively spaced recesses and the male ends carrying exteriorly thereof integral similarly spaced lugs fitted within the recesses of the next adjacent hub, a packing of heat insulating material between said hubs and the 40 shaft, and means carried in fixed relation to the shaft adjacent to its opposite end portions and interengaged with the endmost hubs whereby the various interengaged hubs are held against rotation relative to said 45 shaft.

4. A conveyer element comprising a disk having a sleeve-like hub, integral radial arms carried interiorly of said hub, said hub having a male end and a female end adapted 50 to interfit with the non-corresponding ends of similarly shaped hubs, the female end having therein internal relatively spaced recesses and the male end having exteriorly thereof integral spaced lugs for fitting with 55 in the recess of an adjacent similarly shaped hub.

5. In a furnace conveyer, a shaft, a conveyer element having a sleeve-like hub received over said shaft, arms carried by and 60 extending radially inwardly of said hub and engaging the shaft, said hub having a male and a female end, the male end having an external lug and the female end having an internal recess to receive the lug of an 65 adjacent hub, said hub having an internal

diameter greater than the external diameter of such shaft, and a heat-resisting packing between the shaft and said hub.

6. In a furnace conveyer, a shaft, a conveyer element having a sleeve-like hub of an 70 internal diameter greater than the diameter of the shaft, means carried by the hub and engaging the shaft to maintain the hub in spaced concentric relation to the shaft, said hub having a female end and a male end, the latter adapted to be received within the female end of an adjacent hub, complementary means on the male and female ends for interengagement so as to hold adjacent 75 hubs against relative rotation, and a packing of heat insulating material between the shaft and the hub.

7. In a metallurgical furnace, a shaft, a plurality of work supporting disks mounted on said shaft, each of said disks being provided with a sleeve surrounding said shaft and having inwardly extending lugs for spacing the sleeve from said shaft, each of 85 said sleeves being formed with an enlarged portion at one end receiving an end of the 90 sleeve of the next adjacent sleeve, and insulating material secured between each sleeve and said shaft.

8. In a metallurgical furnace, a shaft, a plurality of work-supporting disks mounted on said shaft, each of said disks being provided with a sleeve surrounding said shaft and having inwardly extending lugs at one end for spacing the sleeve from the 95 shaft, each sleeve having its other end formed with an enlarged portion receiving an end of the next adjacent sleeve, and insulating material secured between each 100 sleeve and said shaft.

9. In a metallurgical furnace, a shaft, a plurality of work-supporting disks mounted on said shaft, each of said disks being provided with a sleeve extending laterally on both sides thereof and provided at one end with inwardly extending lugs engaging 105 said shaft, said sleeve having its other end formed with an enlarged portion receiving an end of the next adjacent sleeve, and insulating material secured between each 110 sleeve and said shaft.

10. A carrier wheel device comprising a shaft, a plurality of wheels associated therewith, and a sleeve surrounding said shaft but spaced therefrom and co-operating with the hubs of the wheels for connecting the 115 wheels to each other.

11. A carrier wheel device comprising a shaft, a plurality of wheels associated therewith, and a sleeve surrounding said shaft but spaced therefrom and co-operating with the hubs of the wheels, the sleeve and hubs having projection and recess engagement for connecting the wheels to each other.

12. A carrier wheel device for annealing furnaces comprising a shaft, a plurality of 120

- wheels associated therewith, and sleeves surrounding said shaft and co-operating with the hubs of the wheels, the sleeves and hubs having projection and recess engagement 5 for connecting the wheels to each other, the sleeves being provided with air pockets for protecting the shaft from the heat of the furnace.
13. A carrier wheel device comprising a shaft, a plurality of wheels provided with hubs having recesses therein associated with the shaft, a plurality of sleeves having projections thereon surrounding the shaft between the wheels, said sleeves being spaced 10 from the shaft and means for connecting the end wheels to the shaft.
14. A carrier wheel device comprising a shaft, a plurality of wheels provided with integral hubs having recesses therein associated with the shaft, a plurality of sleeves having projections thereon surrounding the shaft between the wheels, said sleeves being spaced from the shaft and end sleeves for connecting the end wheels to the shaft.
15. A carrier wheel device for furnaces comprising a shaft, a plurality of wheels provided with integral hubs having recesses therein associated with the shaft, a plurality of sleeves having projections thereon 15 surrounding the shaft between the wheels, and end sleeves connected outside of the furnace to the shaft and provided at their opposite ends with projections cooperating with recesses in the hubs for connecting the end 20 wheels to the shaft.
16. In a conveyer for furnaces, the combination with a rotary shaft, of a plurality of elements carried by said shaft, each of said elements having an internal diameter 25 materially exceeding the outside diameter of said shaft, means disposed inwardly of the elements for maintaining the elements in spaced relation to the shaft, each of said elements being provided with male and female means for interengaging with the next adjacent elements for preventing relative 30 rotary movement thereof.
17. In a conveyer for furnaces, the combination with a rotary shaft, of elements carried by said shaft, and having an internal diameter materially exceeding the diameter of said shaft, certain of the elements having article carrier means of greater outside diameter than the element and having 35 means seating on the shaft whereby the element is maintained in spaced relation to the shaft, and means including interengaging male and female portions on the elements provided with co-operating projections and recesses for preventing relative 40 rotation of the elements.
18. In a conveyer roll for a furnace for heat-treating metallic sheets, the combination of a central shaft, a series of disks 45 mounted thereon, and tubular shields of heat resisting metal engaging said disks, each shield surrounding said shaft and being spaced away therefrom so as to form an air chamber.
19. In a conveyer roll for a furnace for heat-treating metallic sheets, the combination of a central shaft, a series of disks mounted thereon, and tubular shields of heat resisting metal engaging said disks, each shield surrounding said shaft and being spaced away therefrom so as to form an air chamber, said disks having lateral flanges telescopng with said shields. 50
20. In a conveyer roll for a furnace for heat-treating metallic sheets, the combination of a central shaft, a series of disks mounted thereon, and tubular shields of heat resisting metal engaging said disks, each shield surrounding said shaft and being spaced away therefrom so as to form an air chamber, said disks having lateral flanges telescopng with said shields and being perforated within said flanges. 55
- In testimony whereof, I affix my signature.
